UNITED STATES PATENT OFFICE.

HARRY L. OGG, OF NEWTON, IOWA, ASSIGNOR TO AUTOMATIC ELECTRIC WASHER COMPANY, OF NEWTON, IOWA, A CORPORATION.

COMBINED WASHING AND WRINGING MACHINE.

1,222,240.

Specification of Letters Patent. Patented Apr. 10, 1917.

Application filed May 6, 1916. Serial No. 95,897.

To all whom it may concern:

Be it known that I, HARRY L. Ogg, a citizen of the United States, residing at Newton, in the county of Jasper and State of Iowa, have invented certain new and useful Improvements in Combined Washing and Wringing Machines, of which the following is a specification.

This invention relates to combined washing and wringing machines and has as one of its objects to provide novel means for supporting the wringer mechanism so that the same may be adjusted to assume various positions with relation to the tubs and also with relation to a supplemental tub supporting frame structure to suit the convenience of the user of the machine.

Another aim of the invention is to provide means for supporting the wringer mechanism for adjustment in the manner above stated which means will be arranged for swinging movement about the operating or power shaft for the wringer mechanism as a center, thereby avoiding any interference with the gearing for transmitting power from the said shaft to the wringer mechanism regardless of the position to which the mechanism is adjusted.

Another aim of the invention is to provide novel means for holding the wringer mechanism in its various positions of adjustment, which means will effectually hold the said mechanism against accidental displacement after having been adjusted to the desired position and which yet may be conveniently manipulated so as to permit of the mechanism being swung to a new position of adjustment.

Another aim of the invention is to provide between the wringer mechanism and the power shaft therefor, power transmitting gearing so arranged that the direction of rotation of the wringer rolls may be reversed or the gearing may be rendered wholly inactive so as to permit of the wringer mechanism being operated by hand.

Another aim of the invention is to provide power transmitting mechanism between the mechanism and the power shaft of the motor provided for operating the ma-

chine which transmitting mechanism may be adjusted so as to render either the washing mechanism or the wringing mechanism inactive.

Another aim of the invention is to provide a novel construction of wringer mechanism.

In the accompanying drawings—

Fig. 1 is a side elevation of the machine embodying the present invention;

Fig. 2 is a top plan view thereof;

Fig. 3 is a similar view, the tubs being removed;

Fig. 4 is a vertical sectional view taken in a plane between the tubs;

Fig. 5 is a perspective view of the supporting structure for the wringer mechanism;

Fig. 6 is a plan view of an element of the means for supporting the structure shown in Fig. 5 in its various positions of adjustment;

Fig. 7 is a perspective view of a portion of the mechanism for releasing the wringer rolls;

Fig. 8 is a vertical transverse sectional view substantially on the line 8—8 of Fig. 4;

Fig. 9 is a perspective view of the bracket shown in Fig. 6;

Fig. 10 is a horizontal sectional view through a portion of the wringer mechanism;

Fig. 11 is a detail vertical sectional view substantially on the line 11—11 of Fig. 4.

The washing and wringing mechanisms of the machine embodying the present invention are mounted upon a frame which is indicated in general by the numeral 1 and inasmuch as this frame constitutes the subject-matter of a separate application it need not here be specifically described.

The machine embodies two tubs, one indicated by the numeral 2 and the other by the numeral 3 and these tubs are mounted and secured upon the top of the frame 1 in any suitable manner and each is provided with a hinged cover 4 provided with a combined bearing and gear casing 5 in which is rotatably mounted the shaft 6 of the agitator (not shown) which works within the tub, 100

the casing housing the gear for the agitator shaft which gear is indicated by the numeral 7 and the casing being open at one side so as to permit of the projection exteriorly of 65
5 the casing of a portion of the periphery of the gear housed thereby. The gears 7 of the two agitator shafts are driven by reciprocatory rack bars 8 which may be swung into and out of mesh with the respective gears 7
13 and which coact with the said projecting peripheral portions of the respective gears and reciprocate between the same and guide rollers 9 also mounted upon the covers 4. At their outer ends the rack bars 8 are pivotally 70
15 connected, as at 10, to the upper ends of rockers 11 mounted for oscillatory movement in suitable brackets 12 upon the outer or remote sides of the tubs 2 and 3, these rockers being oscillated through the medium 75
20 of motor driven gearing which will now be described and which includes pitman rods 13 pivotally connected to the lower ends of the said rockers. Any suitable type of motor may be employed, but in the drawings there
25 is shown an electric motor indicated by the numeral 14 having the usual power shaft 15 upon which is fixed a gear 16. This gear meshes with a gear 17 fixed upon a shaft 18 which is rotatably mounted in suitable 80
33 brackets 19 and 20 fixed upon the upper sides of base-boards 21 and 22, respectively, mounted within the frame 1. Held for rotation upon the shaft 18 and slideable longitudinally thereon is one member 23 of a clutch 85
35 and in order that this member of the clutch may be shifted into and out of clutch with the other member a shaft 24 is mounted in suitable brackets 25 within the frame and is provided at its lower end with a yoke 26
40 engaging with the clutch member 23 and at its upper end is provided with a lever arm 27 which extends beneath one side of the top of the frame 1 and is supported for movement in a suitable guide 28 upon the under- 90
45 side of the said top of the frame, the lever arm being provided with a handle 29 whereby it may be swung as stated. The other member of the clutch, indicated by the numeral 30, is carried by a pinion 31 which is
50 loose upon the shaft 18 and this pinion is in mesh with gears 32 which are located at opposite sides thereof and which are consequently rotated in opposite directions when the pinion itself rotates with the shaft 18. 95
55 Each of the gears 32 is provided with a crank pin 33 and the inner ends of the pitman rods 13 are connected to these crank pins. Consequently, as the gears 32 rotate the pitman rods will be reciprocated and the 100
60 rockers 11 oscillated whereby to impart opposite reciprocatory motion to the rack bars. The gears 32 are mounted upon shafts 34 which are journaled in bearing portions constituting parts of the bracket 20 heretofore
referred to. The shaft 18 is also suitably 65
geared with the mechanism of the wringer in the manner which will presently be explained.
Secured to the underside of a base-board 35 which is mounted in the top of the frame 1 is a bracket 36 having bearing portions 37 and 38 within which is journaled a shaft 39 and the said bracket 36 is provided at its top between the bearing portion 38 and the bearing portion 37 with a vertical 70
bearing 40 to rotatably receive the lower end of a shaft 41. The upper side of the bracket 36 is provided in vertical alinement with the bearing 40 with a step bearing or socket 42 provided interiorly with a shoulder 43 and fitted to and surrounding the shaft 41 is a tubular bearing standard 44 which fits at its lower end within the bearing socket 42 and rests upon the shoulder 43 in the manner clearly shown in Figs. 4 and 11 of the drawings. The shaft 41 has fixed to its lower end a bevel gear 45 which meshes with a similar gear 46 upon the shaft 39 and also fixed upon the shaft 39 is a sprocket gear 47 about which is trained a sprocket chain 48, 90
the chain passing also about a sprocket gear 49 which is loosely mounted upon the shaft 18, as shown in Figs. 3 and 4 of the drawings. Mounted upon the shaft 18 for rotation therewith and yet slideable thereon is a 95
clutch member 50 designed to coöperate with a clutch member 51 carried by the sprocket gear 49. The clutch member 50 may be shifted into and out of clutch with the member 51 through the medium of a lever 52 100
which is mounted for swinging movement, as at 53, upon the base-board 22 and is provided with a yoke 54 coöoperating with the clutch member 50. It will now be understood that inasmuch as when the motor is in 105
operation the shaft 18 will be continuously rotated, rotary motion may be imparted to the shaft 41 by swinging the lever 52 so as to move the clutch member 50 into clutch with the member 51. The upper portion of the tubular bearing 44 is braced by means of a bracket, which is shown clearly in Fig. 9 of the drawings, and which includes a body 55 having attaching arms 56 which are secured at their outer ends to the adjacent side of one of the tubs, as for example the tub 3. The body portion 55 of the bracket is provided with an opening 57 receiving the upper portion of the tubular bearing 44, the said tubular bearing is 110
further braced by a bracket arm 58 secured to the tub 2 and extending to and secured to the body portion of the bracket 55. Mounted upon the upper side of the body portion of the bracket 55 and secured thereto by suitable bolts 59 is a rack or keeper device comprising a circular body 60 having an upstanding annular flange 61 pro-

vided at intervals with notches 62. Fitted to the upper end of the bearing sleeve 44 above the rack device is a sleeve 63 which is integral with the inner end of a supporting arm 64, the sleeve being secured to the said upper end of the tubular bearing by means of a set screw 65 threaded through the sleeve and bearing against the upper end of the said tubular bearing. The wringer mechanism includes a frame having side members 66 and 67, and the outer end of the supporting arm 64 is secured, as at 68, to the lower end of the side member 66 of the said frame and the said arm is provided near its inner end, or in other words, near the sleeve 63 with an upstanding attaching portion 69 bolted or otherwise secured, as at 70 and 71, to the lower portion of the side member 67. A gear casing 72 is secured to and supported by the side member 67 of the wringer frame and journaled in a bearing 73 secured upon the side member 66 and a bearing 74 constituting a portion of the attaching member 69, is a shaft 75 which projects at one end into the gear casing 72. Loosely mounted upon this shaft in spaced relation are bevel gears 76 and 77 which mesh with a bevel pinion fixed at the upper end of the shaft 41. Mounted upon the shaft 75 for rotation therewith and yet slidable upon the shaft is a double ended clutch 79 which may be shifted selectively into clutch with the gears 76 and 77 through the medium of a shifting arm 80 mounted for swinging movement, as at 81, to the upper side of the gear casing 72. The side members 66 and 67 of the wringer frame are connected at their upper ends by a cross piece 82. Mounted upon the underside of the cross piece 82 is a bracket 83 and mounted for swinging movement within the said bracket upon a pivot bolt 84 fitted through the bracket and through the said cross piece, is an operating lever 85. Connected to this lever 85 at one side of the pivot therefor is one end of a connecting rod, indicated by the numeral 86, the other end of the said rod being connected pivotally, as at 87, to the upper end of the arm 80. It will now be understood that by grasping either end, or if desired, both ends of the lever 85, the lever may be swung so as to rock the arm 80 and thereby shift the double ended clutch 79 into clutch with either of the gears 76 and 77 or to neutral position, as shown in Fig. 4 of the drawings. In order that the lever 85 may be held in any of its positions of adjustment the bracket 83 is provided with a series of openings 88 in which may interchangeably seat a stud 89 upon the underside of the lever, the lever being normally held yieldably in position for engagement of its said stud in the openings 88 by means of a spring 90 fitted to the lower portion of the pivot bolt 84 and bearing at its lower end against the lever and at its upper end against 65 the underside of the cross piece 82. It will now be observed that the gears 76 and 77 are located at opposite sides of the axis of the shaft 41 and consequently the supporting arm 64 may be swung around the shaft as a center so as to position the wringer mechanism at any desired angle with relation to either of the tubs or that member of the frame structure which is to support the auxiliary tub or basket or other receptacle into 75 which the clothes are to be deposited after passage between the wringer rolls. In order that the supporting arm 64 may be held in its various positions of adjustment, a sliding spring pressed pawl 91 is mounted in apertured ears 92 upon the underside of the arm 64 and a spring 93, which is fitted upon the pawl 91 and which bears against one of the said ears 92, yieldably holds the pawl with its outer end in engagement in one or another of the notches 62 in the flange 61 of the rack device heretofore described. In order that the pawl may be retracted thereby to permit of the wringer mechanism to be swung to the desired position, a pivoted 80 hand lever 94 is mounted at the outer end of the arm 64 at the underside of the said arm and connected at one end to this lever is a rod 95, the other end of the rod being connected to the other end of the said pawl 91. It will now be understood that inasmuch as the hand lever 94 is located at the outer end of the supporting arm 64, it may be conveniently grasped and swung upwardly to retract the pawl 91 at the same time the outer 100 end of the said supporting arm 64 is grasped for the purpose of swinging the said arm to adjust the wringer mechanism.

Fixed upon that end of the shaft 75 opposite the end at which the gear 76 is located, 105 is a sprocket gear 96 and trained over this gear and over a similar gear 97 is a sprocket chain 98. The gear 97 is fixed upon the spindle 99 of the lower one of the wringer rolls indicated by the numeral 100, the upper roll being indicated by the numeral 101. The gears 96 and 97 and also the sprocket 110 chain 98 are housed within a casing 102 mounted upon the side member 66 of the wringer frame and by reference to Fig. 4 of the drawings it will be observed that the end of the spindle 99 extends exteriorly of the casing and is squared, as indicated by the numeral 103, for the application thereto by a crank handle (not shown) whereby the 115 wringer rolls may be rotated manually instead of through power derived from the motor 14. Mounted beneath the lower wringer roll 100 is a water-board 104 which is so supported that it may be rocked so 120 as to assume a position inclining downwardly to either side of the vertical plane in which the rolls 100 and 101 are located,

so that the board may be adjusted in accordance with reversal of the direction of rotation of the rolls. The rolls may be subjected to tension whereby to vary the pressure on the clothes passing therebetween through the medium of compression springs 105 arranged within the side members 66 and 67 of the wringer frame and the numeral 106 indicates a follower bar provided at its ends with bearing members 107 designed to bear upon the upper ends of said springs 105. Tension screws 108 bear at their lower ends against the said members 107 and as these screws are tightened the members and the follower bar 106 by which they are carried will be forced downwardly so as to increase the tension of the said springs. In order that the springs may be quickly relieved of tension, means is provided which will now be described. The tension screws 108 have their threaded shanks fitted in sleeves 109 which are rotatably mounted in the ends of the cross piece 82 in the manner clearly shown in Figs. 4 20 and 10 of the drawings and these sleeves are provided at their lower ends each with a laterally projecting lug 110. The said sleeves and their lugs are received within key-hole slots 111 formed in the said ends 30 of the cross piece 82 and it will be understood that when the sleeves are in such position that the lugs 110 will register with the narrower portions of the key-hole slots 111, the sleeves and their lugs may have free 35 upward movement through the ends of the said cross piece. On the other hand it will be apparent that when the sleeves 109 are forced downwardly and then partly rotated the lugs 110 will be moved to position beneath the cross piece 82 in the manner shown 40 in dotted lines in the said Fig. 10 whereby the sleeves will be held against upward movement through the ends of the cross piece until rotated back to the full line position shown in Fig. 10. In order that the sleeves may be so simultaneously turned or rotated, each of the sleeves is provided at its upper end with an arm 112 which extends radially therefrom and a connecting bar 50 113 extends between these arms and is pivotally connected thereto. One of the arms is provided with a hand grip 114 and it will be understood that by swinging this arm both arms will be correspondingly moved 55 and the sleeves 109 will be correspondingly rotated. In order to limit the movement of the parts in one direction, lugs 115 are provided at the inner ends of the arms 112 and are designed to engage against one side of 60 the connecting bar 113 and in order to limit the movement of the parts in the other direction a lug 116 is provided at the inner end of the grip 114 and is designed to engage against the other side or edge of the bar 113. It will now be understood that

when the sleeves are so turned that their lugs 110 will engage beneath the cross piece 82, the tensioning screws 108 may be turned or adjusted so as to move the follower bar 106 downwardly and thereby compress the 70 springs 105. When it is desired to relieve the rolls of tension this may be quickly accomplished by swinging that one of the arms 112, which is provided with the grip 114, so as to rotate the sleeves 109 to position 75 with their lugs registering with the lower ends of the narrower portions of the key-hole slots 111, as shown in full lines in Fig. 10 of the drawings whereupon the springs will be relieved of tension and the sleeves 30 109 will be forced upwardly.

It has heretofore been stated that the wringer mechanism may be swung to assume various positions with relation to the tubs and also with relation to a support for a 85 tub, or other receptacle which is to receive the clothes after passage between the wringer rolls and this support is in the nature of a frame structure or table section 117 hingedly mounted as at 118 at one side 90 of the frame structure 1 and adapted to be swung upward to supporting position, as shown in Fig. 3 of the drawings.

Inasmuch as the shaft 41 is rotatably mounted within the sleeve 44 and this sleeve 95 is of considerable length and is firmly supported at its lower end within the socket 42 and braced near its upper end by the bracket 55, the shaft is afforded a very substantial bearing and vibration is reduced to 100 a minimum while the wringer is in operation.

Having thus described the invention, what is claimed as new is:

1. In a machine of the class described, a 105 bearing socket provided with a supporting shoulder, a tubular upright bearing member seating at its lower end within said socket and resting upon the shoulder, a bracket 110 bracing the upper portion of the said tubular bearing member, a rack member mounted upon the bracket, an arm extending from the said tubular bearing member, wringer mechanism supported by the arm, an operating shaft rotatably mounted within the bearing member, gear connection between the said shaft and the said wringer mechanism, and a pawl carried by the said arm and engaging the said rack member. 115

2. In a machine of the class described, a 120 supporting and bearing device including a socket member, an upright tubular bearing member supported at its lower end for rotation in the socket member, a bracket rotatably supporting the upper end of the said bearing member, a head supported by the bracket and having an annular flange provided at intervals with notches, the upper end of the bearing member extending above the said head, a supporting arm secured 125 130

upon the said upper end of the bearing member, wringer mechanism supported upon the said arm, a pawl mounted upon the underside of the arm and engaging at its 5 end interchangeably in the said notches, a handle member at the outer end of the arm, connection between the handle member and the pawl for actuating the latter, a shaft

journaled in the bearing member, means for rotating the said shaft, and gear connection 10 between the upper end of the shaft and the wringer mechanism.

In testimony whereof I affix my signature.

HARRY L. OGG. [L.S.]
